FIG. 3

INVENTOR:

William S. Elliot

By MacLeod, Calm, Lopeland & Dyer, Atty.

UNITED STATES PATENT OFFICE.

WILLIAM S. ELLIOT, OF NORTHAMPTON, MASSACHUSETTS, ASSIGNOR TO PRO-PHY-LAC-TIC BRUSH COMPANY, OF NORTHAMPTON, MASSACHUSETTS, A CORPORATION OF MASSACHUSETTS.

BRUSH-STAMPING MACHINE.

Application filed November 20, 1925. Serial No. 70,338.

This invention relates in general to the manufacture of brushes, such as tooth brushes, and has for its object particularly, although not exclusively, the provision of improved automatic mechanism for feeding and carrying the brushes into position to be operated upon, as by means of stamping mechanism which in the present instance stamps the lettering on the handles of the brushes.

As a further object of the invention the machine is provided with an intermittently rotatable feed disk or plate which is part of a Geneva motion, this disk having an intermittent rotary movement or step by step movement imparted to it through a driving member forming the other part of the Geneva motion. The feed disk also constitutes a holder for the brush handles and carries them successively into a position of rest beneath a stamping mechanism. In the present machine improved means is also provided for positively rotating the brush holding and feeding disk from a position of rest into a position of rest, so that after each rotative step the brush handle will be accurately positioned and held with relation to the stamping mechanism.

Other objects of this invention will appear in the following description and appended claims, reference being had to the accompanying drawings forming a part of this specification, wherein like reference characters designate corresponding parts in the several views and wherein:

Fig. 1 is a front elevation illustrating a machine constructed in accordance with my invention.

Fig. 2 is a plan view partly broken away thereof.

Fig. 3 is a side elevation illustrating the machine.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

Referring to the drawings, wherein I have

illustrated a present preferred form or embodiment of my invention, it will be seen that the machine comprises a suitable support or pedestal 9 upon which is mounted a stationary table or support 10 and rising from the table 10 is a supporting frame 11 having a forwardly extending overhanging arm 12. Carried by the arm 12 is a reciprocating ram 13 upon which is supported the stamping mechanism, and the ram may be operated in any suitable manner as is well known in the art. A shaft 14 is journalled in suitable bearings in the upright frame 11 and is connected for rotation to a suitable source of power. Carried by the shaft 14 is a sprocket wheel 15 having driving connection with sprocket wheel 16 secured to a stud 17. Mounted on the outer end of the shaft 17 is a mitre gear 18 in mesh with a gear 19 secured to the upper end of a vertical rotary shaft 20. The shaft 20 operates in suitable bearings carried by the upright frame 11 and secured to the lower end of this shaft is a horizontal sprocket wheel 21. The sprocket 21 is connected by means of a chain 22 to a sprocket 23 secured to the lower end of a shaft 24 supported in the outer end of a bracket 25 carried by the support or bed 10.

Secured to the upper end of the shaft 24 is a rotary disk 26 which operates in a circular opening cut or formed at one edge 85 of a stationary bed plate 27. This plate is supported on a post 30 rising from the bed 10, and mounted upon the bed plate is a flat disk or plate 28. The disk 28 forms the brush feeding and holding member of the machine and rotates on a stud 29 projecting centrally thereof from the post 30. A spiral spring 33 embraces the stud or pivot 29 and is interposed between a washer or collar 31 and an adjusting nut 32 threaded on to the upper end of the stud 29. From this construction, it will be seen that the compression spring 33 acts to force the disk 28 into frictional engagement with the stationary bed plate 27 and the force of this spring 100 may be adjusted by means of the adjusting nut 32.

Referring particularly to Fig. 2, it will be seen that the disk or plate 28 is cut away or formed with a series of radial slots 34, 105 the outer portion thereof being arcuate or

curved in form. The rotary disk or driving member 26 is provided with a projecting stud or roller 5 so that upon rotation of the member 26, the stud or roller 5 will successively travel into and out of the radial slots 34.

From the foregoing, it will be seen that the rotary disk 26 and the disk 28 form respectively the driving and driven members of a Geneva motion, and as a result of the co-operation of these members through the medium of the said roller 5 and the radial slots 34, the brush holding and feeding disk 28, which itself forms a part of the Geneva motion, is rotated upon the bed plate 27 with a step by step movement.

Intermediate each adjacent pair of driving slots 34 of the feed disk 28, the latter is provided with straight radial slots or openings 36 which are so constructed and formed as to receive the handle 37 of the article to be stamped such as a tooth brush. Mounted upon the disk 28 are clips or loops 38 at the inner ends of the slots 36 and adapted to assist in retaining the brush handles 37 in position. The bed plate or supporting table 27 is cut away to provide a discharge opening or slot 39 at one side thereof so that at the completion of each intermittent movement of the feed disk 28 a slot 36 will register with the discharge opening or slot 39 in the table, thereby permitting the brush to be discharged therethrough by gravity into a suitable chute 40.

At the stamping side of the feed disk 28 opposite to the delivery point thereof, a support 41 for the table or bed plate 27 is provided, this support resting against the underside of the table and being carried by the bed 10. This support 41 may be adjusted relatively to the bed plate 27 by suitable mechanism operated through the medium of the handwheel 42. The press or ram 13 reciprocates vertically above the support 41 and is provided with a suitable lettering stamp 43. Each brush handle as it is fed in a step by step movement is stamped with suitable lettering when it reaches the position designated A in Fig. 2, and thereafter the brushes are carried around by the feed disk 28 and discharged through the opening 39 in the bed plate 27.

The feed disk 28 is formed intermediate each adjacent pair of radial driving slots 34 with portions 34^a having an arcuate or curved edge 34^b, this edge being concentric with the axis of rotation of the driving disk or member 26. Thus in operation, it will be seen that the stud or roller 5 while travelling into and out of the slots 34 will always be guided in engagement with the curved edge 34^b. These portions, therefore, act to hold the disk 28 against acceleration or momentum, and by means of the spring 33 which forces the feed disk 28 into frictional en-

gagement with the bed plate 27, the rotation of disk 28 is yieldingly resisted. Therefore the arcuate or curved guide portions 34^b co-operate with the stud or roller 5 to cause the feed disk 28 to be rotated from a position of rest into a position of rest and this is assisted by the action of spring 33. As a result of the construction, the disk or holder 28, at each intermittent movement thereof, carries a brush handle accurately into position beneath the stamp 43 so that the lettering will be stamped in the correct place on the handle or brush. It is important to note that the revolving feed plate 28 itself forms a part of the Geneva motion and is given a relatively short period of rest when the stamping takes place and a relatively rapid movement between the stamping operations.

It is to be understood that by describing in detail herein any particular form, structure, or arrangement, it is not intended to limit the invention beyond the terms of the several claims or the requirements of the prior art.

What I claim is:

1. In a machine of the class described, the combination of an intermittently rotatable feeding member having slots and a rotatable driving member having a stud successively operating in said slots and forming a Geneva motion, said intermittently rotatable member having means intermediate each adjacent pair of slots for holding a brush handle, and means for successively operating on the brush handles while in said holding means.

2. In a machine of the class described, the combination of an intermittently rotatable feeding member having slots and a rotatable driving member having a stud successively operating in said slots and forming a Geneva motion, said intermittently rotatable member having a radial slot intermediate each adjacent pair of slots for holding a brush handle, and means for successively stamping the brush handles while in said holding means.

3. In a machine of the class described, the combination of a pair of rotary members having cooperating means for intermittently rotating one from the other and including a stud movable into and out of a slot, said intermittently rotatable member comprising a holder for a plurality of brush handles, and means for successively operating on said handles while the holder is in a position of rest.

4. In a machine of the class described, the combination of a stationary supporting table, a rotatable disk supported for rotation on said table, a rotary driving member, said disk and member having cooperating means for intermittently rotating the disk from the driving member, said disk having radial slots for holding the work therein,

and means for operating on the work in said slots, said table having an opening therein adapted to register successively with said slots for permitting the discharge of the work therethrough.

5. In a machine of the class described, the combination of a horizontally supported table, a horizontally rotatable disk supported on said table and having slots for receiving the work and for supporting the same for operation against the table, a rotary driving member forming with said disk a Geneva motion for intermittently rotating said disk, and means for operating on the work in said slots while the disk is in a position of rest.

6. In a machine of the class described, the combination of an intermittently rotatable disk having means for holding a brush, a rotary driving member for intermittently rotating said disk and having a projecting stud, said disk having radial slots and having the portions thereof between each adjacent pair of slots formed with a curved edge concentric with the axis of rotation of said driving member, means for rotating said driving member to cause said stud to move into and out of a slot in engagement with said curved edge and means for operating on a brush while so held.

7. In a machine of the class described, the combination of an intermittently rotatable disk, a rotary driving member for intermittently rotating said disk and having a projecting stud, said disk having radial slots and having the portions thereof between each adjacent pair of slots formed with a curved edge concentric with the axis of rotation of said driving member, means for rotating said driving member to cause said stud to move into and out of a slot in engagement with said curved edge, means for holding the work between each adjacent pair of slots, and means for operating on

the work while the disk is in a position of rest.

8. In a machine of the class described, the combination of a stationary horizontal table, a horizontally rotatable brush carrying plate supported on said table, a rotary driving member carried beneath said plate and having a stud, said plate having radial slots terminating in curved edges concentric with the axis of rotation of said driving member and having brush holding slots intermediate each adjacent pair of radial slots, means for rotating said driving member to cause said stud to travel into and out of the radial slots and in engagement with said curved edges, resilient means for resisting the rotation of said plate, and means for stamping the brush while said plate is in a position of rest.

9. In a machine of the class described, in combination, a Geneva motion comprising a driving and a driven member having cooperating means for intermittently rotating the driven member from the driving member, and a work engaging tool movable toward and from said driven member, said driven member comprising means for holding a plurality of work pieces and for feeding the same relatively to said tool.

10. In a machine of the class described, the combination of a horizontally supported table, a horizontally rotatable disk supported on said table and having slots for receiving the work and for supporting the same for operation against the table, a rotary driving member forming with said disk a Geneva motion for intermittently rotating said disk, means for operating on the work in said slots while the disk is in a position of rest, and a slot in said table permitting discharge of work.

In testimony whereof I affix my signature.

WILLIAM S. ELLIOT.
